METHOD FOR THE CONTINUOUS REMOVAL OF THE SCALY MATTER FROM HOT-ROLLED, BAND-LIKE IRON PRODUCTS

Ernst Thomas and Bruno Aurin, Hemer, Germany, said
Aurin assignor to Thomas

Application January 24, 1956, Serial No. 561,090

Claims priority, application Germany January 26, 1955

4 Claims. (Cl. 29—81)

This invention relates to a method and plant for the continuous removal of the scaly matter from hot-rolled, band-like iron products, which are drawn in the plant over guide rollers and over slide-bars provided with arc-shaped slide surfaces, whereby the slide-bars and guide rollers are adjustably supported in their position and arranged with respect to one another in undulating or zig-zag-like fashion, and whereby the scaly matter is loosened from the band-iron products by means of a slide-bar arranged in the vertex of a deflecting angle of the iron products.

According to the invention the removal of the scaly matter is facilitated and improved by the feature that band-iron of a thickness of 1 to 5 mm. is guided over the slide-bar at a deflecting angle which for band-iron of 1 mm. thickness is approximately 70 degrees and which for every additional mm. thickness increases at the rate of approximately 10 degrees; that the length of the radius of curvature of the band-iron as well as of the arc-shaped slide surface of the slide-bar is approximately five times the thickness of the band-iron; and that a portion of the scaly matter fed in by the moving band-iron between the slide surface of the bar and the band surface is crushed by the pressure between the slide surface and the band surface and thus utilized as a slide-promoting medium, and thereupon removed from the band by means of brushes.

Because of the comparatively strong deflection of the band the surface of the latter is upset beneath the neutral zone, whereby the loosening process of the scaly matter is started. The thus loosened scaly matter is then crushed under high pressure between the especially hardened and wear-resisting slide surface or pressure-surface of the slide bar and the surface of the band. For this it is important that the pressure surface of the slide-bar is curved according to a comparatively small radius and that it is of comparatively small width. The arc of the pressure surface positioned in the vertex of the deflecting angle is a very short one, so that a strong upsetting pressure and a considerable crushing of the scaly matter results, while, on the other hand, a sharp-edge deflection of the band is reliably avoided. At the same time, the short but strongly rounded-off arc ends of the slide surface of the slide-bar render it possible that a considerable portion of the scaly matter is drawn-in between the pressure surface of the bar and the band and thereby transformed into a powdery slide-promoting medium, whereby the removal of the scaly matter with the aid of brushes is facilitated without injurious effects to the surface of the band.

According to the invention the plant for the continuous removal of the scales from band-iron is provided at the entering end of the band-iron with guide rollers equipped with brakes; at the exit end of the band-iron with pull exerting rollers driven from a motor; and in the area between the aforesaid rollers with additional guide rollers and with at least one slide-bar provided with means for its adjustment in height with respect to adjacent

2

guiding means, and whereby said slide-bar or bars and said adjacent guiding means are arranged in zig-zag relation with respect to one another in such manner that the band-iron forms the legs of an acute angle adjustable between 70 and 120 degrees and in whose vertex the slide-bar is arranged. Furthermore, the slide-bar is provided with an arc-shaped slide surface having its radius of curvature correspond in length to approximately five times the thickness of the band-iron, whereby the thickness of the slide-bar is at least equal to the length of the radius of curvature of the slide surface, but smaller than twice the length of that radius. The invention further proposes to arrange the slide-bar exchangeably in a guide slot of a supporting body, and to provide the supporting body with means adapted to clampingly secure the slide bar in its position. According to the invention two contrivances of this type may be arranged successively behind each other, so that the scaly matter can be successively removed from both of the faces of the band. The slide-bar should preferably consist of hard metal.

It has further been found that the aforescribed method and plant are also well suited for producing, simultaneously with the removal of the scaly matter, a reduction in thickness of the band-iron treated. For this purpose the invention produces in the band between the brake rollers at the entering end and the pull exerting rollers at the exit end of the plant a tensile stress in such manner that, with the aid of the slide-bars, the band is thereby stretched beyond its range of elasticity and thus reduced in thickness for 20 to 30%.

In cases in which, in addition to the removal of the scaly matter, the band is to be stretched for a reduction of its thickness, the invention proposes to arrange in the plant a plurality of slide bars or pressure bars successively behind one another, that is to say, alternately on the upper surface and lower surface of the band, so that the band is pulled successively a plurality of times over such slide bars or pressure bars. In conformity with the reduction in thickness thus obtained, the angle of deflection is then adjusted in such manner that it is more acute toward the exit end than toward the entering end of the band.

For the production of considerable reductions in thickness it is then possible to pass the band a plurality of times through the same contrivance or through a plurality of similar contrivances successively arranged behind one another, whereby simultaneously the band may be subjected to heat-treatment.

Additional features and advantages of the invention will be understood from a consideration of the following detailed description taken in connection with the accompanying drawings, forming a part of this specification and in which an embodiment of the invention has been shown by way of example. However, we wish to say that the invention is not confined to any strict conformity with the showing of the drawings, but may be changed or modified, so long as such changes or modifications mark no material departure from the salient features of the invention as expressed in the appending claims.

60 In the drawings, in which like parts have been referred to by the same reference numerals in all of the several figures:

Fig. 1 is a central vertical section of a plant for the removal of scaly matter from band-iron, that is to say, from the lower face of the latter;

Fig. 2 is likewise a central vertical section of a continuation of the plant of Fig. 1, for the removal of the scaly matter from the upper face of the band;

Fig. 3 is a perspective view of a portion of the slide-bar and of the means for exchangeably securing it in its position;

Fig. 4 is a diagrammatic illustration, showing a plu-

rality of slide-bars or pressure bars successively arranged behind one another in zig-zag fashion between the brake rollers at the entering end and pull exerting rollers at the exit end of the band-iron;

Fig. 5 is a detail view, on an enlarged scale, showing a vertical cross-section through the upper end of the slide-bar.

Referring now to the drawings in detail, the reference numeral 1 (see Figs. 1 and 2) designates the band-iron or sheet metal running off a reel (not illustrated in the drawings) and passing first between the pair of feed rollers 2, of which at least one is driven from a motor. By means of these feed rollers 2 the band-iron is fed through the brake rollers 3. In the embodiment illustrated in the drawings the invention provides five brake rollers, some of which are braked either directly or at their ends. These rollers simultaneously serve as a means for the straightening or flattening of the band-iron. In the drawing the braking of the rollers 3 is effected with the aid of the diagrammatically illustrated braking means 4. The brake power may be adapted for adjustment by means of spring pressure. From these rollers 3 the band iron passes into the plant section 5 in which for the guidance of the band the rollers 6, 7, 8 and 9 are accommodated. Arranged between the rollers 7 and 8, on a supporting body 10, is a slide-bar 11. The supporting body 10 is vertically adjustable by means of the spindle 12. The rollers 7 and 8 are adapted for adjustment in vertical direction by means of the spindles 13. Positioned beneath the rollers 8 is a brush 14 driven from a motor 15. The band-iron 1 is guided via the rollers 6, 7, 8, 9 and the slide-bar 11 in zig-zag-like fashion, whereby it is important that the band, in dependence upon its thickness, is deflected to such an extent that between the two band portions *a* and *b* an angle *x* is formed, which is adapted for adjustment between 70 degrees and 120 degrees. From the plant section 5 the band-iron then passes into the plant section 16 in which the band is guided over a plurality of rollers 17, 18, 19, 20, 21 in undulating fashion, and whereby beneath the rollers 18 and 20 the brushes 22 and 23 are arranged which are driven from the motor 24. From the plant section 16 the band passes into the plant section 25. Accommodated in this section are the motor-driven rollers 26 around which the band passes in such manner that the rollers 26 are thereby caused to pull the band through the entire scale-removing plant, that is to say, against the brake resistance of the brake rollers 3.

The device as illustrated in Fig. 1 serves the purpose of removing the scales from one face of the band. For the removal of the scales from the other face of the band the latter may be passed a second time through the contrivance of Fig. 1. However, in this case, the band has to be turned first through an angle of 180 degrees, so that the side of the band which at first was down is then up. For the continuous removal of the scales from both sides of the band, the latter has to successively pass also through the contrivance shown in Fig. 2 of the drawings. The construction of the portion of the plant shown in Fig. 2 corresponds substantially to the construction of the plant-portion illustrated in Fig. 1. The only difference being that in the plant-section 27 the guide rollers and the brush are somewhat differently arranged or adjusted, and that the slide-bar or pressure bar 11 and its supporting body 10 are adjusted by means of the upwardly extending spindle 12, so that the pressure of the bar 11 is exerted upon the upper face of the band-iron, and that the angle *x* formed by the band portions *a* and *b* is open in upward direction. The brush 14, in this case, is positioned above the guide roller 8. In the plant-section 28 the brushes are likewise arranged above the rollers, as in this case the upper face of the band has to be brushed.

The slide-bars 11 arranged in the aforesaid working sections 5 and 27 consist of hard metal and are provided

with a slide surface 29 forming a section of an arc of a circle (see Fig. 5). The radius *r* of this arc-shaped slide surface is approximately five times the length of the thickness *s* of the band-iron. The thickness *y* of the slide-bar 11 should exceed in length the length of the radius *r*, but should be shorter than the double length of the radius. The slide surface 29 is at its ends likewise of curved formation and, therefore, merges without edges into the vertically extending side walls of the slide-bar. As shown in Fig. 3, the bar 11 is mounted in a recess 30 of the stationary supporting body 10 and secured in its position by the pressure exerted against it by a detachable bar 31 adapted for tensioning by means of screws 32. The supporting body 10 is fastened by means of screws 33 on supporting means which, with the aid of guiding means 34 (see Fig. 1), are shiftably adjustable in vertical direction in the machine frame. The slide-bar 11 is exchangeably supported between the supporting body 10 and the supporting and tensioning bar 31. The exchange of the bar is necessary whenever band-iron of a different thickness *s* has to be treated for the removal of the scales, as in this case slide-bars of a different thickness *y* and different slide surface 29 are needed. It will be seen that by means of the detachable and adjustable bar 31 slide-bars of various thicknesses can be arranged in the recess or slot 30.

In the embodiment as hereinbefore described the removal of the scales from the band-iron proceeds as follows:

The band is arranged in tensioned condition between the pull exerting rollers 26 of the plant-section 25 and the brake rollers 3, so that exertion of pull by the rollers 26 results in the pulling of one face of the band across the surface of the slide-bar 11 arranged in the plant-section 5. The band, therefore, is continuously pulled in conformity with its adjusted feeding speed and at a comparatively small angle over the curved surface 29 of the bar 11. The small arc formed between the band portions *a* and *b* is equally large as or slightly larger than the arc 29, so that the scaly matter is fed by the movement of the band between the surface 29 and the inner face of the band. Because of the high pressure the scaly matter not yet separated from the band is crushed and thus serves as a slide-promoting medium for the band in the small area of contact between the slide-bar 11 and the band. This powdery and now completely loosened scaly matter can thereupon easily be removed by the brushes 14, 22, 23 which the band subsequently passes, so that a perfectly clean and completely uninjured band surface is obtained.

For carrying out the invention the following dimensions are preferably employed, whereby *s* is the thickness of the band, *r* the radius of curvature of the slide-bar, and *x* the angle of deflection of the band:

<i>s</i> =1 mm.	<i>r</i> =5 mm.	<i>x</i> =70 degrees
<i>s</i> =2 mm.	<i>r</i> =10 mm.	<i>x</i> =80 degrees
<i>s</i> =3 mm.	<i>r</i> =15 mm.	<i>x</i> =90 degrees
<i>s</i> =4 mm.	<i>r</i> =20 mm.	<i>x</i> =100 degrees
<i>s</i> =5 mm.	<i>r</i> =25 mm.	<i>x</i> =110 degrees

whereby for the radius *r* and the angle *x* the permissible variation is $\pm 5\%$.

Fig. 5 shows clearly that the bar 11 does not rest with any sharp edge against the inner face of the band, and that the scaly matter is pulled or fed into a substantially wedge-like gap formed between the upper surface of the bar and the inner face of the band, whereby the scaly matter is crushed and completely loosened from the band, without injurious effect to the inner face of the band.

The device as illustrated in Figs. 1 and 2 of the drawings is also well suited for reducing, simultaneously with the removal of the scales, the thickness *s* of the band-iron. Through alteration of the brake resistance of the rollers 3 and with the aid of a corresponding force of pull provided at the rollers 26 it is possible to subject

the band-iron in the area of the slide-bar 11 to such a degree of tensioning that a plastic deformation is produced and that thereby a reduction in thickness between 20 to 30% is obtained. Because of the constantly uniform pulling speed and because of the likewise constantly uniform brake resistance, the reduction in thickness is also a uniform one. The scaly matter utilized as a slide-promoting medium facilitates the orderly operation of the device and prevents the band-iron from getting stuck at the bar 11.

For reducing the thickness of the band it is also possible to devise the plant as diagrammatically illustrated in Fig. 4 of the drawings. For this purpose the invention proposes to arrange in the plant-sections 5 or 27 a plurality of slide-bars 11 in zig-zag-relation with respect to one another, so that alternately the upper face or lower face of the band is treated. In order to take care of the ensuing reduction in thickness of the band it is then advisable to arrange the deflecting means 11 in such manner that the angle x is more acute in the direction toward the pull exerting rollers 26, i.e. that the angle x' is smaller than the angle x .

What we claim as new and desire to secure by Letters Patent of the United States is:

1. A method for the continuous separation of scale from the surfaces of hot-rolled sheet iron band comprising guiding and pulling the sheet iron band in zigzag formation under tension over a stationary and adjustable curved slide surface, pulling the band over the curved slide surface at an angle having long legs and adjustable by moving the slide surface with the angle depending upon the thickness of the band and which is approximately 70° to 110° for a thickness of 1 to 5 mm., the crown width of the curved slide surface being in contact with the surface of the sheet iron with the radius of curvature only a few times greater in length than the thickness of the band so that the slide surface extends between approximately vertical side surfaces with the distance determined by the curvature radius of the slide surface, and this distance being at least the same but smaller than double its radius of curvature, so that a part of the scale separated from the sheet iron will be drawn along the sheet iron and crushed between it and the slide surface and emerges from the slide surface, and finally removing the scale from the band surface.

2. A method for the continuous removal of scaly matter from the surfaces of hot-rolled iron according to claim 1, in which the step is included of imparting a tensile stress simultaneously on the band with the re-

moval of the scaly matter to produce a reduction in thickness of the band by passing the band over said slide surface of the bar with such tensile stress that the band is thereby stretched beyond its elastic limit.

- 5 3. A method for the continuous removal of scaly matter from the surfaces of hot-rolled iron according to claim 1, in which the step is included of imparting a tensile stress simultaneously on the stressed band with the removal of the scaly matter to produce a reduction 10 in thickness of the band by passing the band over said slide surface with such tensile stress that the band is thereby stretched beyond its elastic limit, and reduced in thickness in conformity with the adjusted degree of tensile stress by 20 to 30 percent.
- 15 4. Method for the continuous removal of scaly matter from the surface of hot-rolled iron bands, comprising pulling the bands under tension in zigzag formation over a stationary and adjustable arc-shaped slide surface with the surface forming an angle of deflection in 20 the band relative to the vertex and adjusting the angle of deflection to approximately 70 degrees for 1 mm. thickness of the band increasing for every additional mm. band thickness up to 5 mm. by approximately 10 degrees, and the radius of curvature of said slide surface corresponding in length to approximately five times the thickness of the band, utilizing the scaly matter created by the passing band as a slide promoting medium between the slide surface and the band and loosened and crushed to a powdery substance by the force between the 30 slide surface and the band, and brushing and removing the powdery substance from the band.
